UNITED STATES PATENT OFFICE.

MACKEY K. MALONE, OF WILLS POINT, TEXAS.

BUSHING REMOVER.

Application filed March 21, 1925. Serial No. 17,298.

The device forming the subject matter of this application is adapted to be used for removing bushings in general, and, in particular, for removing bushings on various 5 parts of motor cars. The invention has for its object, the provision of a strong and simple tool so constructed that bushings of many different diameters may be handled.

It is within the province of the disclosure 10 to improved generally and to enhance the utility of devices of that sort to which the invention appertains.

With the above and other objects in view which will appear as the description proceeds, the invention resides in the combination and arrangement of parts and in the details of construction hereinafter described and claimed, it being understood that changes in the precise embodiment of the 20 invention herein disclosed may be made within the scope of what is claimed without departing from the spirit of the invention.

In the accompanying drawings:—

25 Figure 1 shows in elevation, a tool constructed in accordance with the invention;

Figure 2 is a longitudinal section wherein parts remain in elevation, a bushing being engaged with one of the shoulders;

30 Figure 3 is a cross section on the line 3—3 of Figure 1; and

Figure 4 is a cross section on the line 4—4 of Figure 1.

The tool forming the subject matter of this application preferably is made of metal throughout and comprises a main member 1 including a head 2 joined to a disk-like body 3 from which projects a shank 4 carrying a stem 5 having an extension 6 connected to a tip 7 provided with a threaded end 8. The diameter of the body 3 is less than the diameter of the head 2, and, consequently, the lower end of the head 2 forms a first shoulder 9. The diameter of the shank 4 is less than the diameter of the body 3, and the lower end of the body 3 forms a second shoulder 10. The diameter of the stem 5 is less than the diameter of the shank 4, and the lower end of the shank 4 forms a third shoulder 11. The diameter of the extension 6 is less than the diameter of the stem 5, and the lower end of the stem 5 forms a fourth shoulder 12. The diameter of the tip 7 is less than the diameter of the extension 6, and the lower end of the extension 6 forms a fifth shoulder 14.

The tool includes a tubular auxiliary member 15 surrounding the stem 5, the extension 6 and the tip 7 of the main member 1, the auxiliary member having an end portion 16 whereinto the part 8 of the main member 1 is threaded, thereby to bind the opposite end of the auxiliary member 15 against the shoulder 11 of the main member 1. The auxiliary member 15 includes a sleeve 17 at the lower end of which there is a collar 18 carrying a casing 19 having a reduced end 20. The collar 18 is of less diameter than the sleeve 17, and, consequently, the lower end of the sleeve 17 forms a first shoulder 21. The casing 19 is of less diameter than the collar 18, and, consequently, the lower end of the collar 18 forms a second shoulder 22. A part 20 of the auxiliary member 15 is of less diameter than the casing 19, and, thus, the lower end of the casing 19 forms a third shoulder 23. The head 2 of the main member 1, and the part 17 of the auxiliary member 15 are grooved longitudinally, as at 24, so as to permit the 80 parts specified to clear rivets and other obstacles which may be in the way whilst a bushing is being driven out.

The part 2 serves as a striking head, adapted to receive a hammer-blow. When 85 the parts are assembled as shown in Figures 1 and 2, the shoulders 23, 22 and 24 may be used, and, under some conditions, the shoulders 10 and 9 may be used also. By removing the auxiliary member 15, the shoulders 14, 12 and 11 of the main member 1 are made accessible, and the shoulders 10 and 9 are made to be of wider utility than they are when the auxiliary member is in place, as shown in the drawings. The shoulder 11 exercises a twofold office, in that it may be used for driving a bushing, and in that it may be used, also, as an abutment for one end of the auxiliary member 15, as clearly shown in Figures 1 and 2. The parts 2, 3, 4, 5, 6, 7, 17, 18, 19 and 20 are of different diameters, producing the three different shoulders 23, 22 and 21 on the auxiliary member 15, and producing the five different shoulders 14, 12, 11, 10 and 9 on the main member 1. In view of the foregoing, the tool may be used upon bushings of many different diameters, and has a wide field of application and use.

Generally stated, the device forming the 110 subject matter of this application is a tool which comprises a rod 1 having shoulders

(such as the shoulder 12) adapted to be used for removing a bushing, a tubular member 17 being threaded at 8 on the rod 1 and having shoulders (such as the shoulder 22) for removal of a bushing B, as indicated in Figure 2. In operation, the end 2 of the rod 1 is struck, to force the bushing B out of any part wherewith it may be engaged.

Having thus described the invention, what is claimed is:—

1. In a bushing remover, a main member having transverse brush-engaging shoulders, and an auxiliary member having a trans-

verse brush-engaging shoulder, the auxiliary member housing one of the transverse shoulders of the main member and abutting against another of the transverse shoulders of the main member.

2. A device of the class described, constructed as set forth in claim 1, and further characterized by the fact that the end of the auxiliary member is threaded upon the end of the main member.

In testimony that I claim the foregoing as my own, I have hereto affixed my signature.

MACKEY K. MALONE.
